UNITED STATES PATENT OFFICE.

FREDERIC AUMONIER, OF LONDON, ENGLAND.

DESIGN FOR WALL-PAPER.

SPECIFICATION forming part of Design No. 22,969, dated December 19, 1893.

Application filed November 20, 1893. Serial No. 491,521. Term of patent 3½ years. Registered in England March 3, 1893, No. 208,515.

To all whom it may concern:

Be it known that I, FREDERIC AUMONIER, (trading as Wm. WOOLLAMS & Co.,) a subject of the Queen of Great Britain, and a resident of 110 High Street, near Manchester Square, London, England, have invented a new and useful Design for Wall-Paper, (registered in Great Britain on March 3, 1893, No. 208,515,) of which the following is a specification.

10 This design for wall paper, consisting of frieze, filling, and dado, is represented by the accompanying drawing.

The frieze consists of an upper and lower beading ornamented, the intermediate being 15 a zigzag flower stem from which leaves and branches appear at intervals, the intermediate being filled in from the upper part by sea anemones, and the other by star fish, the rays of which are connected by an openworked 20 web.

The filling is composed of alternate vertical

combinations of fleur-de-lis surmounted by scroll like leaves, above which is a winged insect whose body is of nut shape and surrounded by rays of light. This part of the 25 design is surmounted by a fountain like capping and inclosed by rays of light thrown off from a luminous stem on a dark background.

The dado is a combination of tulips and leaves partitioned by bars having ornamental 30 centers scalloped oblongs inclosing thistle like flowers and leaves.

I claim—

The design for wall paper, substantially as herein shown and described.

The 10th day of March, 1893.

FREDERIC AUMONIER.
